UNITED STATES PATENT OFFICE.

KARL PALME, OF PHILADELPHIA, PENNSYLVANIA.

CIRCULAR-KNITTING MACHINE.

SPECIFICATION forming part of Letters Patent No. 698,549, dated April 29, 1902.

Application filed August 21, 1901. Serial No. 72,761. (No model.)

To all whom it may concern:

- Be it known that I, KARL PALME, residing in the city and county of Philadelphia and State of Pennsylvania, have invented certain new and useful Improvements in Circular-Knitting Machines, of which the following is a full, clear, and exact description, reference being had to the accompanying drawings, forming a part of this specification.
- 10 The object of this invention is to provide in a circular-knitting machine a simple and efficient construction and organization of mechanism whereby a web comprising a seamless tubular section and a wholly or partially fashioned flat section may be produced. Such a web may be utilized as a stocking-leg blank or as a complete stocking-blank, as the length and configuration of the flat portion of the web may determine.
- 15 The primary feature of my invention resides in a certain independently-movable cam so constructed and arranged in relation to the knitting-cams as to be movable either above or between the butts of adjacent needles, as desired, together with means for imparting the requisite adjustments to the said cam at predetermined intervals during the knitting operation, as will be hereinafter particularly described and claimed.
- 20 The invention also comprises novel structural features and combinations of parts, which will hereinafter appear.

In the drawings, Figure 1 is a plan of a portion of a circular-knitting machine embodying my invention. Fig. 2 is a detail of the latch and slide devices. Fig. 3 is a vertical section as on the line 3 3 of Fig. 1, including the needle-cylinder, the cam-cylinder having been moved a quarter-turn. Fig. 4 is a development of the interior of the cam-cylinder and adjuncts. Fig. 5 is a sectional detail as on the line 5 5 of Fig. 1. Fig. 6 is an elevation of the double cam-head for controlling the positions of the needle-picker. Fig. 7 is a sectional detail as on the line 7 7 of Fig. 1. Fig. 8 is a detail of the switch-cam and the pressure-stem therefor. Figs. 9, 10, and 11 are diagrams illustrating the operation of the switch-cam at different stages of the fashioning process.

1 denotes the bed of the machine; 2, the stationary needle-cylinder thereon; 4, the

needles; 6, the rotatable cam-cylinder, and 8 the knitting-cams. These cams comprise the laterally-disposed stitch-cams *a*, the adjacent 55 raising-cams *b*, leading to the supporting-ledge *c* for the heels of the upthrown needles, the two-part guide-cam *d*, and the centrally-disposed switch-cam *e*.

The cam-cylinder is provided around its 60 lower edge with bevel-gear teeth 9, with which coat the teeth of the usual bevel driving-gear, (not shown,) whereby the cam-cylinder may be either continuously rotated or oscillated about the needle-cylinder to actuate the 65 needles for the production of a tubular or flat web, as desired.

According to the preferred type of my invention I first form on the machine a flat web, either wholly or partially fashioned, and I 70 then produce a tubular continuation thereof, the construction, arrangement, and operation of the switch-cam being such that the cylinder may be oscillated even though all the needles be in active position. This switch- 75 cam in the form illustrated comprises a depending wedge-shaped member provided at its upper or larger end with a laterally-projecting pivot-stud 10, which is mounted in a vertically-movable slide 11, fitted to a guide-way in the wall of the cam-cylinder. This slide is located centrally of the knitting-cams, so that by adjustment of the slide the switch-cam may be moved between or raised above the stitch-cams.

The switch-cam *e* is maintained normally in a central position by the action upon its pivot-stud of a spring-pressed stem 12. This stem is fitted at its lower end to a vertical socket in the upper portion of the slide, so as 90 to bear upon an opposing flattened portion of the pivot-stud, the upper end of the slide being guided in a bracket 13 on the wall of the cam-cylinder. A spring 14, encircling the stem, bears against a shoulder thereon 95 and against the bracket in a manner to maintain the stem normally depressed. By this construction it will be seen that though the switch-cam be oscillated from side to side by impact with the opposing needle-heels, so as 100 to direct them to one or the other of the stitch-cams, it will normally resume its central position. When the slide is in its down or normal position, the switch-cam lies be-

tween the stitch-cams, and hence as the knitting-cams are turned about the needle-cylinder the switch-cam engages the opposing needle-heels and directs them down into the 5 path of the knitting-cams; but when, on the other hand, the slide is raised the switch-cam lies above the plane of the needle-heels and passes idly over the same, and hence such needles remain inactive.

10 As a simple and efficient means to raise and lower the slide at predetermined intervals I provide said slide with an outwardly-projecting stud 15 and mount on the bed of the machine an oscillatory cam-lever 16, which 15 may be moved to set its cam portion 17 into or out of the path of the stud, as desired. When the cam portion is in the path of the stud, the stud rides upon the same, and thereby raises the slide sufficiently to move the 20 switch-cam out of action, a suitable latch device being provided to maintain the slide raised for a prescribed period. In the present instance the lever is fulcrumed on the bed of the machine by a stem 18, which depends below the bed. This stem is shouldered, as at 25 19, to engage the two sides of the lever, and its depending portion is encircled by a spring 20, which acting against a cross-pin 21 on the stem and against the under side of the 30 bed serves to maintain the stem normally depressed. The stem is provided at its upper end with a handle 22, whereby the stem, and perforce the lever, may be raised against the stress of the spring, in which case the lever 35 35 may be turned laterally beyond the path of the stud on the slide. The outer extremity of the lever is beveled on its respective edges, as at 23, and a spring-controlled plunger 24 is mounted in a casing on the bed-plate, so 40 as to take against the beveled portions of the lever as the latter is swung from side to side during the operation of the machine, thereby locking the lever in its respective positions. The acting end of the plunger is V-shaped to 45 engage the correspondingly-beveled portions of the lever. The bed-plate is provided with laterally-disposed lugs 25, in which are fitted set-screws 26, which serve as adjustable stops to determine the throw of the lever 16. This 50 50 lever is swung from side to side during the oscillations of the cam-cylinder, so as to bring the cam 17 into position for timely coöperation with the stud 15, the movement of the lever being effected by the engagement therewith 55 of a projection 27, carried by a bracket 28, on the cam-cylinder. In the present instance the end of the cam-lever 16 is socketed, as at 29, and the projection during the rotation of the cam-cylinder registers with the socket 60 60 similarly to a gear-tooth, and thereby swings the lever from one side to the other as the direction of movement of the cylinder may determine.

The latch device above referred to for temporarily supporting the slide-bar in its raised position comprises a lever 30, fulcrumed on the flange of the cam-cylinder, the longer arm

of the lever being pressed normally against the side of the slide by the action of a spring 31, interposed between the shorter arm of the lever and the cam-cylinder. Hence when the slide is raised the lever moves automatically below the same and supports it. The longer arm of the lever is provided on its under side with a camway 32, and the bed of the machine is provided with a suitably-located cam-piece 33, which is adapted to register with said camway at a prescribed point in the movement of the cam-cylinder, so as to retract the latch-lever from the under side of the slide, 80 and thus permit the latter to resume its normal or down position.

Preparatory to the production of flat-fashioned work—as, for example, a gradually-widened web—all the fashioning-needles are 85 moved successively into action until the entire circle of needles shall have been rendered operative. This being done, the cam-cylinder is continuously rotated and tubular work accomplished.

90 Any usual or approved type of needle-picking mechanism may be employed to render the fashioning-needles operative. In the present instance I have illustrated a construction including the bracket 28 on the cam-cylinder, a vertical pintle 34, mounted on the bracket, and a picker-arm 35, pivoted at one end of said pintle and extended into the cam-cylinder, through an opening in the wall of the latter. On the cam-cylinder is a V-shaped 100 cam 36, at the apex of which the picker-arm is held by means of a suitable spring 37, the inner extremity of the arm being notched on opposite sides, as at 38, for engagement with the opposing needle-heels, so that during the 105 oscillation of the cam-cylinder the raised or idle needles engaged by the arm will be moved thereby down into active position.

110 Normally the needle-picker is active. It is, however, inactive during the knitting of prescribed courses in fashioning work and also during the production of tubular work. A simple and efficient means to render the picker periodically inactive is as follows: Overhanging the picker-arm is one limb of 115 an angle-piece 39, the other limb whereof extends through a vertically-movable post 40. By depressing this post the angle-piece bears upon the picker-arm and lowers it to an inactive position, and by raising the post the 120 arm resumes its normal condition. In the post are two sockets 41 41, one above the other, and in a recess in the bracket 28 is a ball 42, that automatically registers with either of the sockets opposed thereto as the 125 vertical position of the post may determine, thereby temporarily locking the post in its position of adjustment. The ball is maintained yieldingly against the post by a spring 43, confined within the recess of the bracket. 130

At a suitable point on the bed of the machine is a bracket 44, in which is slidably fitted a vertical rod 45, carrying at its upper end a double cam-head, the upper or the

lower member of which, as the vertical position of the rod may determine, is adapted to be engaged by the outwardly-projecting portion of the angle-piece 39 to effect the depression or the elevation of the post, as desired. When the rod is in its raised or normal position, the lower cam 46 is in service, and when the rod is depressed the upper cam 47 is in active position. Encircling the rod 10 45 is a spring 48, which bearing against the bracket and cam-head maintains the rod normally raised. To the lower end of the rod is pivoted one arm of a lever 49, which is fulcrumed to a bracket 50, depending from the bed-plate, the other arm of said lever overhanging a suitable pattern-chain 51, which is carried and impelled by a sprocket-wheel 52 on a suitable shaft 53. This chain is provided with suitably-disposed high links 54, which 15 20 at predetermined intervals abut against and raise the opposing arm of the lever 49, thereby effecting the depression of the rod and its cam-head. When the high links escape the lever, the rod and cam-head resume their normal condition.

The operation of the machine may be briefly described as follows: Assume it be desired to produce a stocking-leg blank having a selvaged flat-fashioned portion for a part 30 of its length and a seamless tubular portion for the remainder of its length. At the outset all the needles, excepting those representing the narrow end of the web, are raised to the idle level—that is, above the guide-cams *d*. 35 These raised needles constitute the fashioning-needles and occupy a space on each side of the central line, (marked *x* in the drawings.) The cam-lever 16 is then set in operative position. This done, the machine is started, the 40 pattern-chain 51 thereof being advanced step by step and the cam-cylinder being oscillated with a stroke exceeding a complete revolution. In one stroke of the cylinder the projection 27 engages the notched cam-lever 16, swings 45 it laterally toward the opposing stop, and passes onward, as shown in Fig. 1. As the knitting-cams approach the end of the stroke the stud of slide 11 rides upon the cam 17, thereby raising the slide and the switch-cam. At 50 the same time the latch-lever 30 passes under the slide and maintains it elevated. Hence in the continued movement of the cylinder the butts of the needles are cleared from the stitch-cams. (See Fig. 9.) In the return 55 stroke of the cams the stud passes freely above the cam 17; but as the switch-cam reaches the point *x* the lever 30 by its engagement with the cam-piece 33 is retracted from beneath the slide, thereby permitting the latter 60 and its switch-cam to descend. (See Fig. 10.) In the continued movement of the cylinder the depressed switch-cam directs the opposing needle-heels into the path of the stitch-cams. (See Fig. 11.) In this stroke the projection 65 27 reengages the notch of the lever 16 and swings it to the opposite side of the line *x* for engagement by the stud of the slide as the

knitting-cams approach the end of the stroke. During the oscillations of the cam-cylinder the needle-picker is rendered active and idle 70 at predetermined intervals, so that the end fashioning-needles are moved into action for certain courses until the entire circle of needles are in operation. Thereupon the cam-lever is swung entirely out of action, so as 75 to permit the switch-cam to remain in operation, and at the same time the needle-picker becomes idle. Continuous rotation of the cylinder is then effected and a seamless tube of a predetermined length produced. The narrow portion of the blank thus formed may have added thereto the ankle, heel, foot, and toe of a stocking, and the edges of the flat-fashioned portion may be seamed or otherwise connected, thus producing a stocking 85 having a full-fashioned leg.

Instead of forming solely the leg-blank my machine may be operated to produce a complete stocking-blank. In that case the blank will be commenced at the toe part, the toe, 90 foot, heel, and ankle being knitted in a flat web by oscillations of the cam-cylinder and proper manipulation of the needles. Then the lower fashioned portion of the leg may be produced, as above described, following which 95 the tubular portion of the leg may be formed. Upon the completion of the leg the edges of the flat portion of the web from the toe to the tubular portion may be seamed or otherwise connected.

I claim—

1. In a circular-knitting machine, the combination of the needle-cylinder, the needles, including fashioning-needles, the rotatable and oscillatory cam-cylinder, the knitting-cams, including stitch-cams, a switch-cam, and means operated by the oscillations of the cam-cylinder for rendering said switch-cam active and inactive at a point or points centrally of the fashioning-needles, or substantially so, together with picking mechanism for the fashioning-needles, and means for rendering said mechanism idle and active at predetermined intervals.

2. In a circular-knitting machine, the combination of the needle-cylinder, its needles, including fashioning-needles, the rotatable and oscillatory cam-cylinder, the knitting-cams, including stitch-cams, a pivoted switch-cam, and means operated by the oscillations of the cam-cylinder for rendering said switch-cam active and inactive at a point or points centrally of the fashioning-needles, or substantially so, together with picking mechanism for the fashioning-needles, and means for rendering said mechanism idle and active at predetermined intervals.

3. In a circular-knitting machine, the combination of the needle-cylinder, its needles, including fashioning-needles, the rotatable and oscillatory cam-cylinder, the knitting-cams, including stitch-cams, a pivoted switch-cam, means for normally maintaining the same in central position, and means operated by the

- oscillations of the cam-cylinder for rendering said switch-cam active and inactive at a point or points centrally of the fashioning-needles, or substantially so.
5. In a circular-knitting machine, the combination with the needle-cylinder, its needles, including fashioning-needles, the rotatable and oscillatory cam-cylinder, and the knitting-cams, of a vertically-movable support, a switch-cam thereon, and means for automatically raising and lowering said support to move the switch-cam above and between said knitting-cams at a point or points centrally of the fashioning-needles, together with picking mechanism for the fashioning-needles, and means for rendering said mechanism idle and active at predetermined intervals.
5. In a circular-knitting machine, the combination with the needle-cylinder, its needles, including fashioning-needles, the rotatable and oscillatory cam-cylinder, and the knitting-cams, of a vertically-movable support, a pivoted switch-cam thereon, and means for automatically raising and lowering said support to move the switch-cam above and between said knitting-cams at a point or points centrally of the fashioning-needles, or substantially so, together with picking mechanism for the fashioning-needles, and means for rendering said mechanism idle and active at predetermined intervals.
6. In a circular-knitting machine, the combination with the needle-cylinder, its needles, including fashioning-needles the rotatable and oscillatory cam-cylinder and the knitting-cams, of a vertically-movable support, a pivoted switch-cam thereon, means for maintaining said cam normally in central position, and means for automatically raising and lowering said support to move the switch-cam above and between said knitting-cams at a point or points centrally of the fashioning-needles, or substantially so.
7. In a circular-knitting machine, the combination with the needle-cylinder, its needles, including fashioning-needles, the rotatable and oscillatory cam-cylinder and the knitting-cams, of the vertically-movable support, a switch-cam thereon adapted to be set between and above the knitting-cams at a point or points centrally of the fashioning-needles, or substantially so, means for normally depressing said support, means for raising the same, a latch device for maintaining said slide elevated, and means for tripping said device to release the slide.
8. In a circular-knitting machine, the combination with the needle-cylinder, its needles, including fashioning-needles, the rotatable and oscillatory cam-cylinder, and the knitting-cams, of a vertically-movable support, a switch-cam thereon adapted to be set between and above said knitting-cams, at a point or points centrally of the fashioning-needles, or substantially so, means for normally depressing said support, a cam movable in proximity to the rotary path of the support, means on the support to engage said cam and effect the elevation of the support, a latch device for maintaining said support elevated, and means for tripping said device to release the support.
9. In a circular-knitting machine, the combination with the cam-cylinder and the knitting-cams, of a vertically-movable slide, a switch-cam thereon movable between or above said knitting-cams as desired, means for normally depressing said slide, a cam-lever movable in proximity to the rotary path of the slide, means on the cam-cylinder for swinging said lever from side to side according to the stroke of said cylinder, means on the slide to engage said cam and effect the elevation of the slide, a latch device for maintaining said slide elevated, and means for tripping said device to release the slide.
10. In a circular-knitting machine, the combination of the needle-cylinder, its needles, including fashioning-needles the rotatable and oscillatory cam-cylinder, the knitting-cams, including stitch-cams, a switch-cam, means for automatically rendering said switch-cam active and inactive at a point or points centrally of the fashioning-needles, or substantially so, picking mechanism for the fashioning-needles, and means for rendering said mechanism idle and active at predetermined intervals.
11. In a circular-knitting machine, the combination with the cam-cylinder and its knitting-cams, including the stitch-cams, of a vertically-movable support, a pivoted switch-cam, means for maintaining said switch-cam yieldingly in a centrally-depending position.
- In testimony whereof I have hereunto affixed my signature in the presence of two subscribing witnesses.
